Primary Examiner — Elizabeth Albert*(74) Attorney, Agent, or Firm* — Vedder Price P.C.(57) **CLAIM**

The ornamental design for a book stand, as shown and described.

DESCRIPTION

FIG. 1 is a front view of a book stand showing my new design;
FIG. 2 is a rear view thereof;
FIG. 3 is a plan view thereof;
FIG. 4 is a bottom view thereof;
FIG. 5 is a right side view thereof;
FIG. 6 is a sectional view thereof taken along the line 6-6 in FIG. 1;
FIG. 7 is a sectional view thereof taken along the line 7-7 in FIG. 4;
FIG. 8 is a perspective view thereof;
FIG. 9 is a front view of the supporting frame shown without the partitions for convenience of illustration;
FIG. 10 is a rear view thereof;
FIG. 11 is a top plan view thereof;
FIG. 12 is a bottom plan view thereof;
FIG. 13 is a front view of a partition shown without the other partition or supporting frame for convenience of illustration;
FIG. 14 is a rear view thereof;
FIG. 15 is a top plan view thereof;
FIG. 16 is a bottom plan view thereof;
FIG. 17 is a right side view thereof;
FIG. 18 is an exploded perspective view of the book stand of FIG. 1; and,
FIG. 19 is a perspective view thereof, stacked.
The broken lines showing a book stand in FIG. 19 are included for the purpose of showing a portion that forms no part of the claimed design.
